(57) **CLAIM**

The ornamental design for a taillight for a vehicle, as shown and described.

DESCRIPTION

This application contains subject matter related to the following U.S. design patent applications:

Application Ser. No. 29/486,314, filed herewith and entitled “vehicle, toy, and/or replicas thereof”; and

Application Ser. No. 29/486,316, filed herewith and entitled “vehicle, toy, and/or replicas thereof”.

FIG. 1 is a front view of a taillight for a vehicle according to the design;

FIG. 2 is a left, front perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

The distortion line shown in FIG. 4 is caused by light refraction at a seam where two pieces of material forming the transparent outer portion of the design meet.
